DESIGN FOR A TEXTILE FABRIC OR SIMILAR ARTICLE

Gwenyth Waugh, New York, N. Y.

Application February 17, 1939, Serial No. 83,051

Term of patent 3½ years

To all whom it may concern:

Be it known that I, Gwenyth Waugh, a citizen of the United States, residing at 14 West 9th Street, New York, New York, have invented a new, original, and ornamental Design for a Textile Fabric or Similar Article, of which the following is a specification, reference being had to the accompanying drawing forming a part thereof.

The figure is a plan view of a textile fabric showing my new design. The dot and dash lines on the drawing outline substantially a design unit, which unit is repeated in regular succession as indicated by the extensions beyond the unit boundaries.

I claim:

The ornamental design for a textile fabric or similar article, as shown and described.

GWENYTH WAUGH.
